UNITED STATES PATENT OFFICE.

JEAN MARTIAL LOBIT, OF BROOKLYN, NEW YORK.

KEYBOARD.

Application filed August 21, 1924. Serial No. 733,260.

This invention relates to key-boards. More specifically it relates to key-boards particularly adapted to be employed in combination with or as a part of assembling mechanisms of slug-casting machines such as the linotype, intertype, etc., although it may be employed to advantage in other machines.

One of the objects of the present invention is to provide a novel construction of key-board.

Another object is to provide a key-board in which no power is employed and, preferably, in which no springs are employed.

15 A further object is to provide a key-board in which any selected one of the key-levers and connected parts may be removed from the key-board without removing the remaining key-levers.

20 A still further object is to provide a key-board which is comparatively simple in construction but reliable in operation, and durable. Other objects and advantages will appear as the invention is hereinafter described.

Referring to the drawings which illustrate what I now consider a preferred form of my invention,

25 Fig. 1 is a sectional side elevation of the key-board;

Fig. 2 is a plan view, partly in section and partly broken away, of the key-board shown in Fig. 1;

30 Fig. 3 is a fragmentary detail plan view, partly in section, of certain of the parts shown in Figs. 1 and 2;

Fig. 4 is a fragmentary detail sectional elevation of certain of the parts shown in Figs. 1, 2 and 3.

40 Referring to the drawings, it will be seen that the key-board comprises a plurality of keys 10, each provided with a corresponding one of a plurality of key-levers 11. Each key-lever 11 is mounted for pivotal movement about a rod 12, detachably secured at each end to the frame 13 of the key-board, as shown in Figs. 2 and 3. I prefer to employ the following structure for pivotally connecting the key-levers 11 to the rod 12.

45 Slidably mounted upon the rod 12 are a plurality of bushings or sleeves 14, there being as many of these as there are key-levers 11, there being one for each key-lever. Each

of the sleeves 14 comprises a hub portion and a flange portion. Each of the key-levers 11 is provided with an opening 15 which is circular but not in the form of a complete or closed circle as it terminates at the shoulder portions 16, 17 (see Figs. 1, 3 and 4). The diameter of each of the circular 55 openings 15 is substantially the same as the external diameter of the hub portion of each of the sleeves 14, there being sufficient clearance so that each key-lever 11 may rotate or oscillate about the hub of its corresponding sleeve 14. It will be noted that the distance between the shoulders 16 and 17 of each key lever 11 is less than the external diameter 60 of the hub portion of the corresponding sleeve 14. It will be noted further that the distance between the shoulders 16 and 17 of each key-lever 11 is greater than the external diameter of the rod 12. By virtue of this construction, when the parts are assembled 65 and there is no space between the sleeve members 14, each of the key-levers 11 is pivotally movable about the hub portion of its corresponding sleeve 14 and is spaced from adjacent key-levers 11 by the flanges 70 of the sleeves 14. In this assembled position of parts, the key-levers 11 are individually pivotally movable about the axis of the rod 12 but cannot be removed therefrom 75 because, as stated above, the distance between the shoulders 16-17 is less than the external diameter of the hub portions of the sleeves 14. If it be desired to remove any key-lever 11 from the rod 12, i. e. from the key-board, this may be effected by sliding 80 the sleeve 14 upon which that particular key-lever 11 is mounted away from the adjacent sleeve 14 (as shown in Fig. 3). The particular key-lever 11 may then be slid off the hub of its sleeve 14 (as shown in Fig. 3) and then removed from the rod 12, 85 because, as stated above, the distance between the shoulders 16-17 is greater than the external diameter of the rod 12 to permit of this detachment.

90 The key-levers 11 and associated parts are held in assembled relationship (Fig. 2) by means of two sleeves 20, slidably mounted on the rod 12 adjacent the opposite ends thereof and adapted to be engaged by nuts 21 which screw-threadedly engage the rod 12. By 95 proper manipulation of the nuts 21 on the

rod 12 the parts may be held in the assembled position (shown in Fig. 2) or the sleeves 14 may be separated to permit the removal of any desired key-lever 11.

5 My key-board is capable of application to and embodiment in various types of assembling machines. For example, it may be substituted for the key-boards now employed in the assembling mechanism of 10 machines such as the linotype, intertype, etc. Among other advantages, it will be noted that no springs or power mechanism are employed in my key-board, the structure is simple, and each and any of the 15 key-levers 11 may be removed from the rod 12 and the key-board for repair or replacement, without removing any of the other key-levers 11. The key board may also be employed in a machine such as that illustrated in my copending United States application Serial No. 582,593, filed August 18, 1922, and entitled "Assembling machines", or as illustrated in my Canadian application Serial No. 290,554, filed June 25, 1924, entitled "Assembling machines". When employed with the last mentioned machines, each key lever 11 is pivotally connected at its rear end to a corresponding one of bars 25 each adapted at its upper 30 end (not shown) to engage and operate a corresponding one of a number of matrix releasing pawls of a magazine positioned over the delivery channels (not shown). In short, the key-board forming the subject 35 matter of the present application may (as indicated in my said Canadian application) be substituted for the main key-board shown in my said copending United States application Serial No. 582,593. Preferably 40 the upper end of each bar 25 is detachable from its supporting structure (not shown) so that each key-lever 11 and its bar 25 are removable as a unit. However, if desired, each key-lever 11 may be made detachable 45 from its corresponding bar 25.

Upon depression and subsequent release of any key 10, it is automatically restored to its original elevated position by gravity, the weight of that portion of each key-lever 11 to the right of the rod 12 (in Fig. 1) and its bar 25 being greater than the weight of the key 10 and that portion of the key-lever to the left of the rod 12. No springs are required, nor is any power 55 mechanism required, in connection with my key-board which is a departure from the key-boards of assembling mechanisms heretofore utilized in practice.

The keys 10 may be provided with the 60 usual indicia, each corresponding to the matrix which is released by that particular key.

In accordance with the provisions of the 65 patent statutes, I have herein described the principle of operation of my invention, to-

gether with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of these may be altered and others omitted without interfering with the more general results outlined, and the invention extends to such use.

What I claim is:

1. A key-board comprising in combination, a plurality of key levers, means pivotally supporting said key levers, and means mounted on said means whereby each of said key levers may be removed from the key-board without releasing the other key levers. 80

2. An assembling mechanism for slug-casting machines comprising in combination, a key-board having individually removable and operable keys, individually operable means for positively maintaining said keys in pivotal relation, and connections adapted to release matrices corresponding to the particular key or keys operated, and gravity means for causing each key to resume normal position after it has been operated. 90

3. In an assembling mechanism for slug-casting machines, a key-board having individually operable keys and key levers and connections adapted to release matrices corresponding to the particular key or keys operated, means pivotally supporting said key levers; and means mounted on said means whereby each of the key levers may be removed from the key-board without removing the other key levers. 100

4. A key board comprising in combination, a shaft, key levers, and sleeves mounted upon said shaft and engaging openings in said key levers whereby the axis of said shaft defines the pivotal loci of said key levers. 110

5. A key-board comprising, in combination, a shaft, a plurality of sleeves mounted on said shaft, a plurality of key levers, each of said key levers having an opening therein with shoulder portions engaging one of said sleeves whereby disengagement of a key lever and a sleeve in a direction other than longitudinally of said shaft is prevented. 115

6. A key-board, comprising, in combination, a shaft, a plurality of sleeves mounted on said shaft, a plurality of key levers, each of said key levers having an opening for engaging said sleeves, said openings having mouths of less width than the diameters of said sleeves, means to space adjacent key levers, and means to maintain said sleeves in contacting relation. 125

7. A key-board comprising, in combination, a shaft, a plurality of sleeves mounted upon said shaft, key levers having openings for engaging said sleeves, means for maintaining said sleeves in contacting relation and for permitting any one of said sleeves to be displaced whereby any one of said

key levers may be disengaged from its sleeve and removed from the key-board without removing any other key lever. 10

In testimony whereof I hereto affix my signature.

JEAN MARTIAL LOBIT.
